UNITED STATES PATENT OFFICE.

RICHARD R. DIETRICH, OF BALTIMORE, MARYLAND.

INTERNAL-EXPLOSIVE ENGINE.

1,340,651.

Specification of Letters Patent. Patented May 18, 1920.

Application filed August 3, 1916. Serial No. 112,891.

To all whom it may concern:

Be it known that I, RICHARD R. DIETRICH, a citizen of the United States, residing at Baltimore city, in the State of Maryland, 5 have invented certain new and useful Improvements in Internal-Explosive Engines, of which the following is a specification.

This invention relates to improvements in internal explosive engines and has for its object to provide novel and improved means 10 for transmitting power from the piston or pistons to the crank or cranks.

In carrying out the invention I may readily vary the number of pistons and cylinders employed, but in the present instance I have diagrammatically shown two pistons and cylinders, and for the purpose of simplification, have omitted to illustrate the admission and exhaust parts and valves, and 20 the ignition devices, which can obviously be supplied by anyone skilled in the art.

The invention is illustrated in the accompanying drawing wherein,—

Figure 1 shows two cylinders, a crank case 25 and crank and also shows two connecting rods both of which connect with a crank through a link, and

Fig. 2 illustrates in a diagrammatic way the positions of the piston and link during 30 a revolution.

Referring to the drawing the numeral 10, designates a casing, the shape of which is immaterial, but is such as to inclose the crank and the moving parts that connect the 35 crank with the pistons. In the present instance two cylinders 11 and 12, respectively are shown at opposite sides of the casing,— one cylinder having a piston 13, and the other a piston 14. The crank-shaft 15, enters the casing, in the present instance, between the inner ends of the two cylinders 40 and said shaft carries a crank 16.

In the structure shown the piston 13, has a connecting rod 17, the outer end 18, of 45 which is pivotally connected to said piston and the inner end 19, of which is pivotally attached to the free end 20, of an oscillating rod 21. This oscillating rod 21, in the present instance, has a lower end 22, which is 50 pivoted at 23, in the lower part of the casing 10, so that the free end 20, of said rod may be swung back and forth between the inner ends of the two cylinders 11 and 12, as the pistons 13 and 14, are reciprocated.

55 The piston 14, also has a rod 24, whose outer end 25 is pivotally connected thereto

and the inner end 26, of which rod is pivotally connected to the upper free end 20, of said oscillating rod.

It will thus be seen that in the present 60 form both connecting rods 17 and 24, have their inner ends connected to the free end 20, of the oscillating rod, and that when one piston makes an inward stroke the other piston will make an outward stroke and thus 65 during the expansion or power stroke of each piston the power exerted thereby will be applied to the free end of the oscillating rod.

A link 27, connects the free end 20, of the 70 oscillating bar 21, with the swinging end or wrist-pin 28, of the crank 16, so that as the said bar-end swings back or forth it causes a forward push or a backward pull on the link 28, which movement is imparted to the 75 crank whereby to swing the latter through a circular path.

It will thus be understood that in accordance with this invention there is interposed between the connecting rod and the crank, a 80 link, whose movement is such as to apply a thrust of the connecting rod on the crank.

By referring to Fig. 2, of the drawing it will be noted that four positions A—B—C and D of the crank and link are shown, and 85 by reference to Fig. 1, three positions A—B and C of the piston in the cylinder are shown. It will be understood that when the link is at position A, the end of the piston will be at line A in Fig. 1; that when the link is at B, the end of the piston will be at line B in said Fig. 1, and when the link is at position C, the piston will be at line C in said Fig. 1.

By comparing the positions of the link 95 shown in Fig. 2, with the positions of the piston shown in Fig. 1, it will be noted that the link has full power when the piston is under full compression and that practically the same pressure is applied to the crank 100 through the link, during the entire revolution of the engine because the position of the link with respect to the connecting rods changes as the pressure in the cylinder decreases.

Having described my invention, I claim.

1. The combination with a plurality of cylinders, of a piston in each cylinder; a connecting-rod for each piston and each rod having an outer end pivoted to a piston 110 and the inner ends of the rods being pivoted on the same axis and thereby mechanically

connected together; a crank-shaft having a crank which latter traverses a circular path in a plane between the two pistons and a link having one end pivotally connected 5 with the crank and the other end of said link being pivotally connected with the two pivoted-together ends of the two connecting- rods.

2. The combination with a crank-case, of
10 a plurality of cylinders extending from the crank-case; a piston in each cylinder; a connecting-rod for each piston each connecting-rod having an outer end that is pivoted to a piston and the inner ends of the connecting-
15 rods being pivotally connected on a common axis; an oscillating rod having one end pivotally connected to the pivoted-together ends of a plurality of connecting-rods and

said oscillating rod extending to one side of the path of movement of the connecting 20 rods and having its remote end pivoted; a crank having its axis on the opposite side of the path of movement of said connecting rods and between the inner ends of the cylinders, and a link having one end pivotally 25 connected on the axis of the pivoted-together connecting and oscillating rods and its other end pivoted to the crank and said link being located in a plane at the side of one of the said connecting-rods. 30

In testimony whereof I affix my signature in the presence of two witnesses.

RICHARD R. DIETRICH.
